UNITED STATES PATENT OFFICE

NICHOLAS SAMANTAS, OF SAN FRANCISCO, CALIFORNIA

PERMANENT HAIR WAVING DEVICE

Application filed August 11, 1930. Serial No. 474,513.

My invention relates to improvements in permanent hair waving devices, and it consists in the combinations, constructions and arrangements hereinafter described and claimed.

An object of my invention is to provide a permanent hair waving device which makes use of a spool having means for holding paper, the paper in turn receiving a strand of hair and being perforated so that steam can pass through the paper and affect the hair during the permanent waving operation.

A still further object lies in the provision of a handle for holding the spool which makes it easier to roll the spool by means of the handle, the handle also being provided with means for swinging the cover of the spool away from the latter when receiving a strand of hair.

The invention also makes use of novel means for locking the spool in place after it has rolled the strand of hair to the desired tightness.

Other objects and advantages will appear as the specification proceeds, and the novel features of the device will be particularly pointed out in the claims hereto annexed.

My invention is illustrated in the accompanying drawings, in which:

Figure 1 is a view showing how the various parts of the device are used,

Figure 2 is a side elevation of a scissor type handle,

Figure 3 illustrates another type of handle,

Figure 4 shows another view of the handle shown in Figure 3,

Figure 5 illustrates the spool,

Figure 6 is a top plan view of the spool,

Figure 7 is a section along the line 7-7 of Figure 5,

Figure 8 is a side elevation of a clip used in the device,

Figures 9 and 10 are views of the clip shown in Figure 8,

Figure 11 shows how the clip holds the spool, and

Figure 12 shows a strip of paper used with the device.

In carrying out my invention I make use of a clip shown in Figures 8, 9 and 10 which

is secured to a strand of hair at a point adjacent to the scalp. As many of these clips are used as needed, although I have only shown one such clip in Figure 1. The clip is composed of a body portion indicated generally at 1, the body consisting of two parts 2 and 3 (see Figure 9), these parts being permanently secured together by suitable fastening means 4 such as pins or rivets. The top of the body 1 has a concave recess 5 therein, and this receives a roller 6. In Figure 8 I show the roller as being pivoted at 7 to an upright 8 that passes between the parts 2 and 3 (see Figure 10) and is secured to these parts by fastening pins 4. The parts 2 and 3 are spaced to allow steam to pass between the same.

The strand or lock of hair is placed between the body 1 and the roller 6 and then the roller is swung from the full-line position shown in Figure 8 into a position paralleling the axis of the body. The free end of the roller 6 carries a hook 9. At the left hand end of the body 1 there is pivoted a fork-shaped member 10. This member is swingable about one of the pins 4 as a pivot, and when swung in an outward direction permits the roller 6 to be swung into closed position. The fork-shaped member 10 can then be swung back so as to receive the hook 9, and a cam 11 carried by the member 10 may be turned by means of a handle 12 so as to lock the roller 6 in closed position. As already stated, the body 1 and the roller 6 are placed near the scalp and enclose a strand of hair which is to be curled.

The end of the strand of hair is now wrapped around a spool shown in detail in Figures 5, 6 and 7. The spool consists of a body portion 13 of the shape shown in Figure 5 and a lid 14, the latter being pivoted to the body 13 by a pin 15. Figures 5 and 6 clearly show how the body 13 has a groove 16 disposed beneath the lid 14, this groove receiving a wire 17.

The lid 14 has teeth 18 formed in one edge thereof and also has a longitudinally-extending slot 19 (see Figures 6 and 7). The spring 17 and the slot 19 are designed to receive strips of paper of the shape shown in Figure 12.

Each strip of paper 20 is preferably provided with a tongue 21 at one end and with perforations 22 in its body portion. The tongue of one tissue paper 20 is passed beneath the spring 17 and is wrapped once around the spool 13 as shown in Figure 7 and then extends away from the spool a short distance. Another piece of tissue paper 20 has its tongue 21 disposed in the slot 19, and then 10 the paper is wrapped around the serrated edge 18 of the lid 14 and extends away from the lid in the manner shown in Figure 7.

The operator now makes use of a handle 23 of the type shown in Figure 2, or can make 15 use of a handle 25 of the type shown in Figures 3 and 4 for supporting the spool during the rolling operation. The handle 23 has a rod 26 designed to enter a socket 27 in the spool 13 (see Figure 5). The rod 26 has a slot 28 disposed off-center for receiving the pin 15 that passes through the socket 27. The lid 14 has arms 28' (see Figure 5) that have inwardly-turned ends for being received in recesses 29 in a semi-tubular member 30 that is pivoted at 31 to the rod 26. The recess 29 receives the inwardly-turned ends of the arms 28', and it will be seen that a movement between the semi-tubular member 30 and the rod 26 will open and close the lid 14. 20 The rod 26 is provided with a handle 32, and the semi-tubular member 30 is provided with a handle 33. The gripping of these handles causes the parts 26 and 30 to move together and to close the lid 14. The moving 25 of the handles away from each other swings the parts 26 and 30 into the position shown in Figure 2, and this movement is limited by a set screw 34.

The operator holds the lid 14 open while 30 placing the end of the strand or lock of hair between the two papers 20 shown in Figure 7. The lid 14 is now closed and the operator starts to roll the hair about the spool 13.

It is desirous to comb the shorter hairs of 35 the strand into the spool while the spool is being rolled. A comb of the type shown in my co-pending application, Serial No. 523,345 filed March 17, 1931, may be used for this purpose.

It might be best to describe the other type 40 of handle 25 at this point. The handle 25 has a rod 39 provided with a slot 40 which acts in the same manner as the rod 26 and the slot 28. A sleeve 41 is slidably mounted on the 45 rod 39 and is urged to the right in Figure 3 by a spring 42. The pin 43 acts as a stop for the spring and at the same time is received in a slot in the sleeve 41 so as to prevent rotation of the sleeve with respect to the 50 rod 39. A disc 44 is secured to the sleeve 41 and may be moved to the left. Figure 4 shows how the left-hand end of the sleeve 41 is provided with lugs 45 that engage with the 55 sides 46 of the arms 28' and swing the lid 14 into open position. The freeing of the 60

disc 44 allows the spring 42 to return it to normal position, and this permits the lid 14 to close.

The operator rotates the spool until it nears the clip 1. It will be noted from Figure 8 that the clip has an end portion 47 in the shape of a hook as shown in Figure 10 and a second end portion 48 having a non-circular recess 49 therein (see Figure 9). The spool 13 (see Figure 5) has a ratchet member 50 with a non-circular end 51 receivable in the recess 49. A spring 52 connects the member 50 with the spool 13 and permits rotation of the spool in one direction with respect to the projection 51 but prevents rotation in the opposite direction. The operator places the projection 51 in the recess 49 after the spool 13 has been rolled up, and then continues to rotate the spool until the hair has been tightened around it to the desired extent. 85 The handle is then removed from the spool and the ratchet prevents the spool from unwinding.

A solution is then applied to the hair, following which the hair is heated in the usual 90 manner. Since these operations form no part of my invention, they need not be described.

Figure 11 shows how the spool 13 is held in the clip 1. The rest of the hair that is 95 to be curled is gone over in the same manner as that already described.

Although I have shown and described two embodiments of my invention, it is to be understood that the same is susceptible of various changes, and I reserve the right to employ such changes as may come within the scope of the claims hereto annexed.

I claim:

1. In combination, a spool having a longitudinally extending groove therein, a clamping member disposed in the groove for holding the end of a paper, and a lid pivoted to the spool and having a slot for receiving the end of a second paper.

2. In combination, a spool having a longitudinally extending groove therein, a clamping member disposed in the groove for holding the end of a paper, and a lid pivoted to the spool and having a slot for receiving the end of a second paper, the paper being perforated and designed to receive a strand of hair therebetween.

3. In combination, a spool having a longitudinally extending groove therein, a clamping member disposed in the groove for holding the end of a paper, and a lid pivoted to the spool and having a slot for receiving the end of a second paper, one edge of the lid being serrated for keeping the hairs of the strand from bunching.

4. In combination, a spool having a recess in one end thereof, a handle removably disposed in the recess, a lid operatively connect-

ed to the spool, and a member carried by the handle and being operatively connected to the lid for opening and closing it.

5. In combination, a spool having a non-circular recess, a lid pivoted to the spool, a handle having a non-circular portion for entering the recess, and means carried by the handle for actuating the lid.

6. In combination, a spool having a non-circular recess, a lid pivoted to the spool, a handle having a non-circular portion for entering the recess, means carried by the handle for actuating the lid, a clip having a non-circular recess therein, and a ratchet carried by 15 said spool and having a non-circular portion received in the clip recess, said handle being rotatable for rolling the hair tightly about the spool while the latter is held in the clip.

7. In combination, a spool having a flexible sheet attached thereto, and a lid having a flexible sheet attached thereto, said spool and lid cooperating with each other for receiving hair therebetween and between the sheets.

25 8. In combination, a spool, and a lid cooperating therewith and having serrations along its edge for keeping the hairs of a strand of hair from bunching.

9. In combination, a spool, and a lid having a flexible sheet attached thereto, said spool, lid, and sheet cooperating with each other for receiving and holding hair.

NICHOLAS SAMANTAS.
